CLAIM

The ornamental design for a handtool, substantially as shown and described.

DESCRIPTION

FIG. 1 is a perspective view of the handtool showing my new design with the various components shown in the open position;

FIG. 2 is a side view from the right hand side of the handtool showing my new design with the various components shown in the closed position.

FIG. 3 is a side view from the left hand side thereof;

FIG. 4 is a top view thereof;

FIG. 5 is a bottom view thereof;

FIG. 6 is a front view thereof; and

FIG. 7 is a rear view of the handtool of my new design.
